UNITED STATES PATENT OFFICE.

ERNEST R. SCHROEDER, OF PATERSON, NEW JERSEY, ASSIGNOR TO AMERICAN CAR AND FOUNDRY COMPANY, OF ST. LOUIS, MISSOURI, A CORPORATION OF NEW JERSEY.

LOCK-LID FOR JOURNAL-BOXES.

1,007,946.

Specification of Letters Patent. Patented May 26, 1914.

Application filed October 6, 1913. Serial No. 793,669.

To all whom it may concern:

Be it known that I, ERNEST R. SCHROEDER, residing at 102 East Seventeenth street, Paterson, Passaic county, New Jersey, and being a citizen of the United States, have invented certain new and useful Improvements in Lock-Lids for Journal-Boxes, of which the following is a full, clear, and exact description, such as will enable others skilled

10 in the art to which it appertains to make and to use the same, reference being had to the accompanying drawings, which illustrate the preferred form of the invention, though it is to be understood that the invention is 15 not limited to the exact details of construction shown and described, as it is obvious that various modifications thereof will occur to persons skilled in the art.

In said drawings: Figure 1 is a front elevation of the journal box with the lock cover in its closed position. Fig. 2 is a longitudinal vertical section thereof, taken along the line 2—2 of Fig. 1, the cover boss being omitted for the sake of clearness. Fig. 25 3 is a plan view of the journal box, partly in section, said section being taken along the line 3—3 of Fig. 2. Fig. 4 is a fragmentary section through the upper portion of the journal box cover, taken along the line 4—4 30 of Fig. 1; and Fig. 5 illustrates a type of key adapted to unlock the journal box cover.

During the rapid transit of trains it has frequently occurred that journal box cover hinge pins have become dislodged and the 35 journal box covers have fallen by the way, leaving the bearings exposed to the dirt and grit swirled into the air and temporarily held in suspension by the suction of the train.

40 It is the object of this invention to provide a cover for journal boxes which may be hinged as usual, but which shall be locked in such manner that even though the cover hinge pin becomes shaken out and lost the 45 journal box cover will be in no wise disturbed, and when desired may be opened for the inspection and oiling of the bearings or closed and locked, at will, quite as well as though the hinge pin were present.

50 Another object is to permit the complete removal of the cover whenever occasion requires it, and this may be quickly done.

The cover locks automatically when pushed in to its closed position, and cannot be 55 opened or removed by unauthorized persons.

Because the construction is simple and inexpensive, as well as efficient, it is practicable and economical to put the covers into use in large numbers in equipping portions of entire railway systems.

60 Referring to the drawings, the journal box 1 is of conventional form, except in that the perforated hinge lug knuckle 2 has integrally cast on each end thereof an annular rib or flange 3. As shown in section in Fig. 2, the annular flange 3 is interrupted throughout the major portion of the upper right hand quadrant of the hinge lug knuckle 2 and for a slight distance in the lower right quadrant, establishing an obliquely disposed opening 4 in the annular flange, and, 65 it is to be understood that a similar opening 4 is present on the opposite end of the hinge lug knuckle 2.

70 In applying the cover 5 to the journal box 1, it is first necessary to invert it, in the direction it normally moves in when in place and being opened, until its lower edge is uppermost and the cover is inclined outwardly but a few degrees from the vertical. Thereupon, perforated partly circular bosses 6, located on the inner ends of the perforated cover hinge knuckles 7 are in a position to be slid into the recesses circumscribed by said annular flanges 3. Said partly circular bosses have oppositely disposed segments of the metal removed, resulting in 75 two flat parallel surfaces spaced apart a distance slightly less than the width of the openings 4 in the flange 3 of the hinge lug knuckle 2. The axes of hinge lug knuckle 2 and the cover hinge knuckles 7 aline themselves, and the cover may then be revolved downwardly into its normal closed position.

80 Or, if it is desired that it should remain in its normal open position for any reason, the cover may be turned down far enough for the free end of the cover spring 8 to rest upon the inclined surface 9 of the hinge lug 2. Thereupon, said cover will remain in 85 its normal open position until manual exertion is employed to close it. With the cover in place, and hence with the perforated hinge knuckles 2 and 7 alined, a cover hinge pin of any suitable kind may be inserted 90 through the perforations in said knuckles, forming an independent pivotal connection between the box and the cover. This is particularly useful in case of damage occurring to the flanges 3 or bosses 6, and forms an 95 100 105 110

efficient temporary substitute hinge connection. And, if, perchance, the lid becomes cracked, so as to be entirely useless, any M. C. B. cover available may be substituted 5 because of the perforated hinge knuckles. And still further, should it be desired to prevent the ready removal of the cover, or to hold it together in case of its becoming cracked throughout its height, the use of 10 a pin passing through the perforated hinge knuckles of said cover and that of the box will accomplish the desired results. The rotary movement of the cover 5 will have caused the integral bosses 6 to assume a position in 15 which their dimensions opposite the openings 4 in the flanges 3 are greater than the width of said openings, and dislodgment or withdrawal of the cover 5 is impossible. In fact, any tendency to return to the initial 20 inserting position first referred to will be resisted by the spring 8, and it can only be accomplished by a deliberate attempt on the part of a person with that object in view. In bringing the cover 5 into its normal 25 closed position, a latch 10, backed by a spring 11, both of which are inclosed by a housing 12 integral with cover 5, encounters the lip 13 of the outer opening of the journal box 1. As it does so, said latch 10 recedes 30 into the housing 12, against the influence of spring 11. Upon the cover 5 coming to rest in its final closed position, latch 10 snaps outwardly and behind the lip 13, locking the cover securely in place. Latch 10 is limited 35 in its movements by a pin 14, which passes through the cover 5, a slot 15 in said latch and the inner vertical wall of the housing 12, said pin being headed or riveted at each end. Not only does the pin 14 limit the throw of 40 latch 10, but it retains the latter and its spring 11 within the housing 12. Besides being locked at its lower extremity, the cover 5 is also locked at its upper end, through the agency of bosses 6 and the annular flanges 45 3 on journal box hinge lug knuckle 2, and it is therefore closed and locked to all except those employees or others who are provided with a key to open it. Such a key is shown at 17 in Fig. 5, and also in Fig. 2, here being 50 inserted through a key hole 16 and into the lock mechanism.

The manipulation of the journal box cover 5 remains the same as in the existing practice, except that the key 15 is inserted 55 through the key hole 16 and upon a partial turn to the right raises the latch 10 out of engagement with the lip 13 of the outer opening of the journal box. The cover may then be raised to its normal open position 60 and held there by cover spring 8 resting upon the inclined surface 9 of the hinge lug 2. To remove the cover, manual pressure must be employed, when it will be further revolved until the flat parallel surfaces of

bosses 6 align with the sides of openings 4. 65 Said cover 5 may then be slid in the direction in which openings 4 lie and so be detached from the journal box 1.

The cover hinge pin referred to hereinbefore has not been shown, as it is entirely unnecessary to the operation of the cover, but it may be used, if desired.

When closed the journal box cover is locked at the top and the bottom, and it cannot become dislodged or lost, nor can it 75 be opened without the aid of a key to retract the latch 10.

What I claim is:—

1. In a journal box, the combination of an integral perforated hinge supporting lug 80 having a knuckle portion, curved flanges on the ends of said knuckle portion, said flanges being interrupted in their circumscription, a cover having perforated hinge knuckles, partly circular perforated bosses 85 thereon with oppositely located cut away portions, said bosses being normally retained and partly inclosed by said curved flanges.

2. In a journal box, the combination of a 90 perforated integral hinge lug, interrupted annular flanges on the ends thereof, and a cover having perforated hinge knuckles, integral perforated bosses thereon substantially conforming, except for a pair of oppositely located cut away segments thereof, to the inner surfaces of said flanges, the distance between said cut away segments being less than the distance between the terminals of said flanges, said flanges normally retaining and partly inclosing said bosses. 95

3. In a journal box, the combination of a hollow perforated integral hinge lug, interrupted annular flanges on the ends thereof, and a cover having perforated hinged 105 knuckles, integral perforated bosses thereon conforming, except for oppositely disposed cut away portions, to that part of the inner surface of said flanges which is of uniform curvature, the distance between said cut 110 away portions of said bosses being less than that between the terminals of said flanges, said bosses being normally embraced by said flanges, but adapted to be withdrawn therefrom. 115

4. In a journal box, the combination of a hollow perforated integral lug formed with interrupted annular integral flanges on the ends thereof, a detachable cover having perforated hinge knuckles, integral perforated 120 bosses thereon surrounded by said flanges except at a gap between the terminals of said flanges, said bosses being provided with oppositely located cut away portions, the distance between which is less than that between the terminals of said flanges. 125

5. In a journal box, the combination of a perforated integral hinge lug, interrupted

annular flanges formed on the ends thereof, a detachable cover having perforated hinge knuckles, integral perforated bosses thereon surrounded by said annular flanges except at a gap between the terminals thereof, said bosses being provided with oppositely located cut away portions, the distance between which is less than that between the terminals of said flanges, a cover-positioning spring attached to said cover and an inclined surface on said hinge lug co-acting with said cover-positioning spring.

6. In a journal box, the combination of an integral perforated hinge lug, a detachable cover having integral hinge lugs containing perforations alining with the perforation of said integral box hinge lug, separable pivotal means partly integral with said box hinge lug and partly with said cover hinge

lugs, and an auxiliary box and cover hinge 20 connection associated with said perforations.

7. In a journal box, the combination of an integral perforated hinge lug, a detachable cover, integral hinge lugs thereon containing perforations alined with the perforations of said integral box hinge lug, auxiliary hinge elements integral with said cover, and other co-acting auxiliary hinge elements integral with said box hinge lug, all of said auxiliary hinge elements being concentric 30 with said perforations.

In witness whereof I have hereunto set my hand in the presence of two witnesses.

ERNEST R. SCHROEDER.
